INCIDENT LIGHT MODIFYING ATTACHMENT
FOR A PHOTOGRAPHIC EXPOSURE METER

Denis Connelly, Littleheath, Hertfordshire, England,
assignor to Sangamo Weston Limited

Filed Jan. 17, 1969, Ser. No. 15,547

Term of patent 14 years

Int. Cl. D16—99
U.S. Cl. D61—1

FIG. 1

FIG. 2

FIG. 3

FIG. 4

FIG. 5

FIG. 1 is a perspective view from below of an incident light modifying attachment for a photographic exposure meter showing my new design;

FIG. 2 is a plan view thereof;

FIG. 3 is a side elevational view thereof;

FIG. 4 is a cross sectional view thereof taken on the line A—A of FIG. 2, and

FIG. 5 is an underneath plan view thereof.

I claim:

The ornamental design for an incident light modifying attachment for a photographic exposure meter, substantially as shown.
